UNITED STATES PATENT OFFICE.

DAVID F. SHOPE, OF PORTLAND, OREGON, ASSIGNOR OF ONE-HALF TO GLEN SHOPE PICKENS, OF FORT SHERIDAN, ILLINOIS, AND ONE-HALF TO BIRDIE SHOPE SNYDER, OF DULUTH, MINNESOTA.

BUILDING BLOCKS.

Application filed November 27, 1925. Serial No. 71,638.

This invention relates to building blocks or tiles, and it has for one of its objects providing blocks that may be very conveniently handled, and constructed so as to 5 provide a maximum amount of compression resistance with the minimum amount of material. Another of the objects of the invention is to produce a heat resisting wall and at the same time a wall that will 10 not cause moisture to condense thereon. Another object is to provide means for filling in fractional portions of blocks without mutilating the blocks themselves. Other objects of the invention will be apparent from a consideration of the accompanying drawings and the following description thereof.

Of the drawings Fig. 1 is a plan view of one of the blocks, the view being taken 20 from the underside thereof; Figs. 2, 3, and 4 are sections along the respective lines 2-2, 3-3, and 4-4; Figs. 5 and 6 are perspective views of bricks which are used for fractional purposes when the dimensions of 25 the space to be filled in are less than the dimensions of the block of Fig. 1; Fig. 7 is an elevation of a wall formed of the blocks; Fig. 8 is a sectional view of the wall along the line 8-8 of Fig. 9; and Fig. 9 is a longitudinal section of a portion of the wall; Fig. 10 is a section along the line 10-10 of Fig. 7; Figs. 11 and 12 are elevations of modified types of walls; and Figs. 13 and 14 are sections along the respective lines 13-13 and 14-14 of Figs. 11 and 12.

Each of the blocks 9 comprises a frame portion 10 having hollows 11 therein. The hollows extend from one side to adjacent the other side, but have the other ends of 40 the openings closed by the web portions 12. The blocks also have hollows 13 which extend to adjacent the other side, and with openings 14 extending clear through the web. These two central openings 13 have 45 flanges 15 which may be grasped by the hand of the workman in handling the block and which thus provide a very convenient handle for manipulating these blocks, especially when being laid with the hollows opening downwardly. In order to 50 strengthen the walls of the blocks I fill in the corners 16 of the hollows as indicated, adding strength to the walls 17 of the blocks. When the blocks are so formed the 55 resistance to compressibility for the mass of the block is substantially at a maximum.

In building walls with these blocks the hollows are ordinarily turned downwardly with the blocks staggered as indicated in Figs. 7 and 9, and mortar or other cementitious material 20 is placed only under the outer longitudinal edges of the walls. As a consequence there is no pressure on the webs which close the ends of the hollows so as to cause fracture of these webs, and the 60 compressibility of the wall is not to any material extent diminished. At the same time by placing the binding material over the outer longitudinal uprights the air is free to circulate, as indicated by arrows of Fig. 9, 65 throughout the entire wall. This provides for such circulation as to prevent dead pockets, and the hollows themselves, together with the circulation of the air, provides a very complete heat insulating wall; so that 70 the heat is retained within the building. This is assisted materially by the use of cementitious material under the longitudinal risers rather than the inner ones or the transverse risers, as there is less material 75 for the heat to travel through when passing from the inside to the outside of the wall.

In building walls it frequently becomes necessary to fill in spaces which are smaller than the individual blocks. Often fractional blocks are provided, or the blocks are broken for this purpose, but either of these expedients is objectionable. The means which I provide for filling in such fractional spaces comprises the furnishing of a smaller 80 block or brick such as is illustrated by Figs. 5 and 6. These bricks are of such shape as to conveniently co-act with the main blocks in filling in the spaces. While I do not wish to be limited to any particular dimensions, 85 yet, in this instance, I prefer to provide a brick 24 which is as long and as high, but which is only about one fourth as wide or deep. I also provide bricks 25 which are as 90 long as the block 9 is wide and which are as high as the block, but the width of which is only a small fraction of the length of the main block, preferably about one sixth. Merely to illustrate, the block 9 may be substantially 12" x 8" x 4", the block 24, 95 12" x 4" x 2", and the block 25, 8" x 4" x 2". Thus, not only may the small bricks 100 be used as fillers for fractional spaces but

their dimensions are such that there seldom needs to be any inconvenience in filling, and they can be easily broken into shorter lengths when necessary.

- 5 As indicated in Fig. 7, the blocks 9 being staggered, even though the window sill may abut against one of the blocks, yet the spaces above and below will need to be filled in with smaller or fractional blocks. In this
10 case bricks 24 may be used to fill in the half space above the window sill and the block 9 on the left, these bricks being placed flatwise and hence filling in, with a suitable amount of mortar, between the sill and the overlying blocks. Similarly with the fractional spaces on the right-hand side of the window sill, they are conveniently filled by broken bricks 26 in the manner indicated, the bricks extending longitudinally in the wall.
15
20 Figs. 11 and 12 illustrate other walls which may be laid with my bricks and blocks. In Fig. 11 the blocks are laid transversely, and the filling in of the spaces adjacent the sills is provided for by the broken
25 bricks 27 and 28. In case of blocks having finished or processed outer surfaces for beauty or waterproofing, certain surfaces of the bricks are correspondingly finished; so that the appearance of the wall is not

affected by the use of bricks in place of the blocks. That is, the outer surfaces of the bricks 27 are finished while the inner bricks 28 need have no finished surfaces.

Fig. 12 shows another design of wall in which the blocks are staggered and run longitudinally with transverse bricks 25 between the adjacent ends of the blocks. In this case a broken brick 29 and 30 may be used for filling in adjacent the sill 40.

I claim:

A wall of building blocks, each of the blocks having hollows therein, and each having openings near its longitudinal central portion extending entirely through the block from one side to the other, said blocks in one row being laid staggered with reference to and spaced from the blocks in the adjacent rows, and with the hollow sides downward, and cementitious material positioned between the exterior wall edges of each block and the adjacent underlying blocks, whereby air can circulate through the blocks, and between the adjacent interior side portions of the blocks, from the bottom of the wall to the top.

In testimony whereof, I hereunto set my hand.

DAVID F. SHOPE.
